UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR AN EXTERIOR OF A HOTEL.

SPECIFICATION forming part of Design No. 19,484, dated December 17, 1889.

Application filed November 19, 1889. Serial No. 330,901. Term of patent 3½ years.

To all whom it may concern:

Be it known that I, WILLIAM KEAYS BENEDICT, of the city and county of New York, in the State of New York, have invented and produced a new and original Design for the Exterior of a Hotel, of which the following is a specification, reference being had to the accompanying drawings, forming a part thereof.

Figure 1 represents a perspective view of a hotel showing my design. Fig. 2 represents a horizontal section or plan of the first story. Fig. 3 represents a horizontal section or plan of the second story.

Similar letters of reference designate corresponding parts in all the figures.

A hotel embodying my design is generally L-shaped in the horizontal section and comprises five stories and an attic story. The first three stories are below the eaves of the roof. The next two stories and the attic story are above the eaves of the roof. The roof is in the form of a gable.

At three corners of the hotel are towers, which towers are surmounted by conical roofs.

Extending upwardly at the front of the hotel and rising from the roof is a tower surmounted by a balcony and a substantially cone-shaped dome.

The first story A of the hotel is surrounded upon two sides with a porch B. Flights of steps C lead up to this porch. The porch has two straight portions a a', and intermediate of the straight portions and at one corner of the hotel a curved portion a''. A substantially rectangularly-shaped bay a³ projects from the front side of the first story, which bay represents a portion of the base of a tower F'. A similarly-shaped bay a⁴ projects from the end. Arc-shaped towers D D' D² rise from the first story. These towers are at three of the corners of the first story. At the rear of the first story a porch D³ is arranged. This porch has a shed-roof D⁴. The second story F is provided with a balcony E, corresponding in shape to the porch B. Above the curved portion a² of the balcony the same is surmounted by an arc-shaped shed-roof c. Extending for a distance along one side of the front of the hotel and from the shed-roof c is a straight shed-roof c'. The towers D D' D² also constitute three of the corners of the sec-

ond story, while a projecting rectangularly-shaped portion e of the tower F' is arranged above the portion a³. Upon the front and between the towers F' D' is a bay F², having 55 rounded corners. The outer walls between the bay F² and the towers D' F' are substantially flat.

At the end of the hotel and on the second story is a rectangularly-shaped bay F³. 60

The third story G upon the front of the hotel is like the front of the second story, being provided with a projecting portion g of the tower D' and a bay g' above the bay F². At the end of the hotel the third story shows 65 a portion g² somewhat elevated above the main portion of the story.

The eaves of the roof H, at the front of the hotel and extending for a distance at h around the end, are in the same horizontal 70 plane. Beyond the portion h is a portion h', the eaves of which are elevated above the eaves of the portion h. Said portion h' also projects outwardly beyond the surface of the portion h and is somewhat higher. At the 75 corners of the roof the towers D D' D² likewise extend upwardly, and are surmounted by conical roofs H'. At the front and between the tower D and tower F' is a dormer-window I. Between the tower F' and the tower D' are 80 three dormer-windows I' I² I³. The dormer-window I² is between the dormer-windows I' I³ and is higher than such windows. At the base of the dormer-window I² is a balcony I⁴. To the rear of the tower D', and between it 85 and the dormer-window I³, is a small dormer-window I⁵, having a "hipped" roof.

At the end of the hotel, and to one side of the tower D, is a small dormer-window J, having a hipped roof, and above the dormer-window J is another small dormer-window J', also having a hipped roof. Upon the portion h' of the roof, and at one side of the dormer-window J, is another small dormer-window J², also having a hipped roof. To the right of the 95 dormer-window J² is a dormer-window J³, at the base of which is a balcony j, which balcony surmounts the rectangular bay F³. To the right of the dormer-window J³ is another dormer-window J⁴. The dormer-windows I', 100 I², I³, J³, and J⁴ have gable roofs. The tower F' rises from the roof H. At its corners are

OVER

pilasters f' . Between the pilasters f' are windows f'' , arranged at different elevations. Above the windows f'' are pilasters f''' , beneath which are consoles f'''' . Above the pilasters f'''' is a cornice f''''' . Above the cornice f''''' are consoles f'''''' . The consoles f'''''' are represented as supporting a balcony f''''''' . Above the balcony f''''''' is a conically-shaped dome K, which dome is represented as supported from pillars K'.

which pillars are arranged inward of the rail to of the balcony f''''''' .

What I claim is—

The design for the exterior of a hotel, substantially as herein shown and described.

WILLIAM K. BENEDICT.
